PANEL OF PLASTIC SHEET MATERIAL OR SIMILAR ARTICLE

Arthur D. Sylvester and Arno H. Scheiding, Rowayton,
Conn., assignors to L. E. Carpenter & Company, Inc.,
Wharton, N. J., a corporation of New Jersey

Application February 25, 1957, Serial No. 44,966

Term of patent 14 years

(Cl. D87—3)

Fig. 1.

Fig. 2.

Fig. 1 is a plan view of a full panel of plastic sheet material embodying our new design; and

Fig. 2 is a vertical sectional view, taken along line II—II of Fig. 1.

We claim:

The ornamental design for a panel of plastic sheet material or similar article, substantially as shown.
